UNITED STATES PATENT OFFICE.

GEORGE N. SHEPARDSON, OF MEMPHIS, TENNESSEE.

MOISTURE-SHIELD FOR MOTORS.

1,322,635.

Specification of Letters Patent. Patented Nov. 25, 1919.

Application filed January 2, 1919, Serial No. 269,264. Renewed October 9, 1919. Serial No. 329,633.

To all whom it may concern:

Be it known that I, GEORGE N. SHEPARDSON, a citizen of the United States of America, and resident of Memphis, in the county 5 of Shelby and State of Tennessee, have invented certain new and useful Improvements in Moisture-Shields for Motors, of which the following is a specification.

This invention relates to attachments for 10 automobiles and particularly to moisture shields for motors, the said invention having for its object the provision of novel means for preventing water from gaining access to the ignition system of an explosive motor when installed in an automobile.

A further object of this invention is to provide novel means for intercepting water which enters joints of automobile hoods and 20 diverting it from the wirings or spark plugs and furthermore to provide a guard for protecting the fan belt of an explosive motor.

A still further object of this invention is to provide shields of the character indicated 25 and novel means for their mounting with respect to the operating parts of an automobile.

A still further object of this invention is to provide a device of the character described 30 which will not interfere with access to the motor or operating parts and which will prove strong and durable as well as efficient and satisfactory in use.

With the foregoing and other objects in 35 view, the invention consists in the details of construction, and in the arrangement and combination of parts to be hereinafter more fully set forth and claimed.

In describing the invention in detail, reference will be had to the accompanying 40 drawings forming part of this specification wherein like characters denote corresponding parts in the several views, and in which—

Figure 1 illustrates a fragment of an automobile showing the invention applied under the hood thereof;

Fig. 2 illustrates a top plan view with the hood removed;

Fig. 3 illustrates an end view with the hood removed;

Fig. 4 illustrates a detail view of the clamp;

Fig. 5 illustrates a perspective view of the shields; and

Fig. 6 illustrates a sectional view showing the manner of anchoring one end of one of the shields.

In these drawings 10 denotes a fragment of an automobile, 11 a brace rod extending from the dash 12 to the radiator 13, the said rod being usually below a joint of the hood of the automobile.

The shield 14 comprises a plate which is supported under the joint between the sections of the hood so that water dripping therethrough will strike the shield and be deflected laterally and away from the spark plugs of the motor. The rear end of the shield has a T-head 15 provided with an upwardly extending flange 16 which is preferably seated in a recess 17 formed in the dash board and it may be secured therein by fastenings 18 such as screws or the like. This anchorage of the rear end of the shield insures against moisture or water gaining access to the wiring or conductors which are usually carried by the dash board.

In order to guard the fan belt 19 of the 80 motor and protect it from water, I provide a shield 20 which is supported in an inclined position on a bracket 21, the arm of the bracket being so positioned as to clear the water circulating connection or hose 22 85 which extends from the radiator 13 to the water jacket of the motor and the said bracket has at its upper end an angular foot 23 which is apertured to receive fastenings 24 by which the outer end of the 90 shield is connected to it. The arm of the bracket also has apertures 25 to receive a U-shaped bolt 26, the loop of which bolt partially encircles the brace rod 11 whereby the bracket is anchored so as to hold the 95 shield 20 in proper position with relation to the fan belt.

The configuration of the shield 20 may be modified to suit particular requirements and the arm of the bracket may be bent to insure 100 its clearing the water connections, while at the same time it reaches into position to hold the shield.

I claim—

1. In a moisture shield for motors, a 105 shield having a flange at one end adapted

to be seated in a recess in the dash board in a transversely inclined position, a bracket, a shield carried by the lower end of the bracket and adapted to guard a fan belt 5 of a motor, a foot on the upper end of the bracket, means for attaching the first mentioned shield to the said foot, and a clamp for securing the bracket to a brace rod of an automobile radiator.

10 2. In a moisture shield for motors, a shield comprising a plate having a T-end, a

flange at the end of the plate, means for securing the flange to a dash board, a bracket, means for securing the bracket to a brace rod of a radiator, a shield on the lower end 15 of the bracket for guarding a fan belt, a foot on the upper end of the bracket extending on an incline, and means for attaching the first mentioned shield to the said foot.

GEORGE N. SHEPARDSON.
